RADIATOR

Fred M. Young, Racine, Wis.

Application April 5, 1937, Serial No. 134,928

6 Claims. (Cl. 257—259)

The present invention relates to radiators used for cooling internal combustion engines particularly larger Diesel engines and the like wherein the radiator is a separate self contained unit, and 5 wherein the circulating pump is mounted on the radiator unit and driven directly thereby through a suitable belt.

The principal object of the present invention is to provide a device which may be manufactured, 10 sold and shipped as a complete independent unit, which is simple, compact and economical.

Another object of the invention is to provide a structure which may be moved about on its base and suitably secured to a foundation and wherein 15 in the device will operate more satisfactorily than if made a part of the engine installation.

To these and other useful ends my invention consists of parts and combinations thereof or 20 their equivalents as described, claimed and shown in the accompanying drawings in which:

Fig. 1 is a front elevation of my complete unit as viewed from the fan and pump side.

Fig. 2 is an end elevation of the unit as illustrated in Figure 1.

Fig. 3 is a fractional section taken on line 3—3 of Figure 1.

Fig. 4 is a section taken on line 4—4 of Figure 2.

Fig. 5 is a section taken on line 5—5 of Figure 2.

Fig. 6 is a fractional section of the pump connection taken on line 6—6 of Figure 1.

Fig. 7 is a fractional section of a modification of the pump connection.

As thus illustrated my invention consists of 35 two side base supporting members 10—10 being secured together on the fan side preferably by means of an inverted U shaped channel 11. Vertically positioned channel members 12 are secured to members 10 as illustrated and spaced 40 from member 11 whereby the circulating pump may be mounted in alignment with the driving means on the fan shaft as illustrated. The core of the unit is designated in its entirety by reference character A and comprises upper header 14 and lower header 15 having therebetween the usual tubes 16 and closely spaced fins 17 through which the tubes extend, as is the custom in radiators of the class.

An important feature of devices of the present 50 class is to provide means for free contraction and expansion of the core tubes. For this purpose I provide means for supporting core A through upper header 14 as follows:

I provide L shaped brackets 18—18 which are 55 suitably secured to header 14 and these brackets

are secured to members 12 by means of bolts 19. I provide guide members 20—20 which are secured to the ends of lower header 15 and are loosely embraced by members 12 as illustrated. Thus it will be seen that the complete core is supported on brackets 18, the lower header being loosely and slidably retained by and between members 12 to thereby provide free expansion and contraction of the radiator tubes. Header 14 clearly answers as a spacing member for the upper ends of members 12; thus clearly if bolts 19 are removed, members 12 may be spread and core A easily moved vertically out of the frame.

Members 10 are secured together at their rear ends by member 11. I provide a suitable spacing member (not shown) between the front ends of members 10, thus providing a substantial frame.

I provide preferably supplemental channel frame members 22—22 which are suitably secured to base members 10 of the unit and to end members 12, as clearly illustrated in Figure 2, by welding or otherwise.

The principal object of members 22 is to provide a suitable support for a transverse member 23 which is preferably made from tubing and of a strength suitable for supporting fan shaft bearing 24, having a supporting base 25 which in turn is preferably welded to member 23, member 23 being welded to members 22 at its ends. Thus I provide a substantial frame-work having a pleasing appearance, for the support of core A, the circulating pump and the fan.

I provide a shaft 26 which is rotatably supported by bearing 24 and having a V belt sheave 27 having preferably four belt grooves, the inner one acting to drive the circulating pump 28 through a V belt 29 and a sheave 30. I mount a suitable fan hub on the inner end of shaft 26, having fan blades 35.

I provide a suitable fan blade shroud 36. 40 This member may be secured to or positioned adjacent the top and bottom headers as illustrated in Figure 3, the sides being secured to members 12. A suitably shaped wire screen guard 37 is detachably secured to the fan shroud 45 36 and is made in halves, the edges of the two halves meeting on the horizontal transverse plane of shaft 26 as illustrated in Figures 1 and 2. Thus this guard may be conveniently removed and replaced. I also provide a wire screen 50 38 for the front of the unit.

In the design shown sheave 27 is preferably provided with four V shaped grooves. The inner groove being positioned for the reception of the belt 29 which operatively connects sheave 55

27 to pump sheave 30, the other three grooves being suitable for the reception of three V belts 40 which are operatively connected to a driving sheave on the engine or an electric motor. I 5 provide means for tightening the driving belt 29 in the following manner:

As illustrated in Figure 1 belts 40 are turned 10 in the direction indicated by arrow. Thus the bottom belt will be the loose one. I position 10 idler sheave 41 on a bearing bracket 42, this bracket being provided with slotted openings on both sides of the bearing and end members 12 are provided with a number of suitable openings 43 for the reception of bolts 44 for securing the 15 bracket to its adjusted position. Thus the bracket may be raised or lowered for the purpose of tightening or loosening the belts. Both members 12 are provided with openings 43, thus the fan may be driven from either side of the 20 unit.

Pump 28 is provided with a supporting bracket 50 at each side of which are provided slotted openings for the reception of bolts 51. Member 11 is provided with a number of openings for 25 the reception of bolts 51, thus the pump may be moved on its support to a position suitable for the proper adjustment of the driving belt.

Referring now to Figures 1 and 6. The tube 30 connection between header 15 and pump 28, which in its entirety is designated by reference character B, comprises tube ends 60-60 and a connecting sleeve 61 which is adapted to loosely 35 embrace the tube ends and having at each end a stuffing box nut 62, being screw threaded on the ends of the sleeve. The sleeve ends and nuts are adapted to receive packing rings 63-63; thus when it is desired to move pump 28 for adjusting the tautness of belt 29, one or both nuts may be loosened and again tightened when the pump 40 has been suitably positioned. In Figure 7 the connections between the tube ends are illustrated as being made by means of a rubber hose 64 having the conventional hose clamps 65-65. The 45 advantage of a rubber hose connection as illustrated in Figure 7, is that there will be provided a yielding connection between the pump and bottom of the core unit.

In most installations I provide an overflow tank 67 having a connection 68 to header 14 and a filler cap 69 having a small orifice as is the custom in filler caps for radiators. Pump 28 is provided with an outlet tube 52 which is preferably connected to the bottom of the cooling jackets of the engine. I provide a tube 65 55 which extends through header 14 and being provided with spaced openings 66. This tube may be connected to the top of the engine jackets from either end; thus the cooling water may move from header 15 through pump 28, thence 60 from pump outlet 52 to the engine jacket, thence from the engine jacket into tube 65 as indicated by arrow, whence it is distributed into jacket 14 through openings 66.

Thus it will be seen that the pump, fan, wire 65 screens or core A may each be easily removed and replaced; that core A is suspended from its top, the bottom being slidably embraced by end members 12; that the unit is strong and simple, the frame and shields providing adequate protection for the fan and core and that the assembly has a pleasing appearance.

Pump 28 is preferably of the centrifugal type, the body of the pump being secured to the base by means of a circular gasket and holding bolts, whereby this body may be reversed. As illus-

trated, outlet 52 is in alignment with an opening in members 10 and 22 (see Figure 2); thus the body may be turned or reversed whereby outlet 52 points in the opposite direction from that shown, if desired.

Clearly core A may be supported through the bottom header, the top header being slidably held between members 12. In this design however, a cross member between the tops of members 12 would be essential; however in the design shown in Figure 1, the upper ends of members 12 are secured together by means of the top header.

Having thus shown and described my invention, I claim:

1. A device of the class described, comprising side base members, vertically positioned channels secured to the front end of said base members and having their flanges turned inwardly, a radiator core comprising upper and lower headers 20 having tubes therebetween and a multiplicity of fins through which said tubes extend, one of said headers at its ends being secured to said channels, the ends of the other header having brackets which are slidably embraced by said channels, 25 vertically positioned supplemental frame members secured to the rear end of said base members and extending vertically therefrom to a point midway said channels and secured thereto and having a connecting brace member between the 30 upper ends thereof, said brace member adapted to rotatably support a fan midway the ends thereof, a transverse member secured to the rear end of said base, a multiple V belt sheave secured to the rear end of the shaft of said fan, a cooling 35 liquid circulating pump having a V belt sheave and a belt forming an operative connection to one of the grooves of said fan sheave, a main belt idler sheave secured to one of said vertical members having means for vertical adjustment, 40 said pump having a tube connection to said lower header.

2. A device of the class described, comprising side base members, vertically positioned channels secured to the front end of said base members 45 and having their flanges turned inwardly, a radiator core comprising upper and lower headers having tubes therebetween and a multiplicity of fins through which said tubes extend, one of said headers at its ends being secured to said channels, the ends of the other header being slidably 50 mounted on said channels, vertically positioned supplemental frame members secured to the rear end of said base members and extending vertically therefrom to a point midway said channels and secured thereto and having a connecting 55 brace member between the upper ends thereof, said brace member adapted to rotatably support a fan midway the ends thereof, a transverse member secured to the rear end of said base, a 60 multiple V belt sheave secured to the rear end of the shaft of said fan, a cooling liquid circulating pump having a V belt sheave and a belt forming an operative connection to one of the grooves of said fan sheave, a main belt idler sheave secured 65 to one of said vertical members having means for vertical adjustment, said pump having a tube connection to said lower header.

3. A device as recited in claim 1 including, said tube connection comprising two tubes, their ends 70 spaced apart and having an adjustable connection therebetween.

4. A device as recited in claim 1 including, said tube connection comprising two tubes, their ends 75 spaced apart and being loosely embraced by a

sleeve having end stuffing box nuts and packing material therefor.

5. A device as recited in claim 1 including, a shroud for said fan having a shield attached thereto being formed in upper and lower halves adapted to surround the exposed portion of the blades of said fan.

6. A device as recited in claim 2 including, said upper header having an inlet connection and an over-flow tank connected to the top thereof, said tank having means whereby vapor may escape therefrom.

FRED M. YOUNG.
